UNITED STATES PATENT OFFICE.

GEORGE E. REBER, OF READING, PENNSYLVANIA.

DESIGN FOR A BADGE OR LIKE ARTICLE.

60,263.

Specification for Design.

Patented Jan. 17, 1922.

Application filed August 5, 1921. Serial No. 490,139. Term of patent 14 years.

To all whom it may concern:

Be it known that I, GEORGE E. REBER, a citizen of the United States, residing at Reading, in the county of Berks and State of Pennsylvania, have invented a certain new, original, and ornamental Design for a Badge or like Article, of which the following is a specification, reference being had to the accompanying drawing, forming part thereof.

The figure is a face view of a badge or article of like nature, showing my new design.

I claim,—

The ornamental design for a badge or like article, as shown.

In testimony whereof I affix my signature

GEORGE E. REBER.
